Patented June 11, 1968

211,330

AUTOMOBILE FRONT FENDER OR SIMILAR ARTICLE

Robert G. Casas, 1183 N. Western Ave.,
Los Angeles, Calif. 90029

Filed Nov. 3, 1967, Ser. No. 9,262

Term of patent 7 years

(Cl. D14—3)

FIG. 1.

FIG. 2.

FIG. 3.

FIG. 4.

FIG. 5.

FIG. 6.

FIGURE 1 is a perspective view of an automobile front fender or similar article showing my new design.

FIGURE 2 is a side elevational view of the right side of the automobile front fender or similar article shown in FIGURE 1.

FIGURE 3 is a front view thereof.

FIGURE 4 is a side elevational view of the left side thereof.

FIGURE 5 is a rear view thereof.

FIGURE 6 is a top plan view thereof.

I claim:

The ornamental design for an automobile front fender or similar article, substantially as shown.
